INVENTOR

Victor J. Evans

ATTORNEY

UNITED STATES PATENT OFFICE.

RALPH N. LONGSWORTH, OF SOMERSET, KENTUCKY.

ADJUSTABLE GOLF-CLUB HEAD.

Application filed April 30, 1927. Serial No. 188,012.

This invention relates to improvements in golf clubs, the general object of the invention being to provide means for adjustably connecting the head of the club to the shaft 5 or handle and for enabling the club to be used either as a right-hand or a left hand one, as well as making available either face of the club as a striking face.

Another object of the invention is to provide simple means for permitting the head to be adjusted and locked in adjusted position by a part of the shaft.

This invention also consists in certain other features of construction and in the 15 combination and arrangement of the several parts, to be hereinafter fully described, illustrated in the accompanying drawings and specifically pointed out in the appended claims.

20 In describing my invention in detail, reference will be had to the accompanying drawings wherein like characters denote like or corresponding parts throughout the several views, and in which:

25 Figure 1 is an elevation of the club.

Figure 2 is a central transverse sectional view.

Figure 3 is a longitudinal sectional view through the head.

30 Figure 4 is a top plan view.

Figure 5 is a sectional detail view showing a modification.

In these views, 1 indicates the head of the club which is provided with a flat or 35 straight face 2 and a beveled face 3, the ends of the head being rounded, as shown at 4. A circular hole 5 is formed in the center of the head, said hole passing through the flat face and terminating short of the 40 beveled face. An elongated hole 6 having tapered ends is formed in the upper face of the head and has its small end communicating with the hole 5. A cylindrical plug 7 fits in the hole 5 and this plug is split, as 45 shown at 8, and it is also provided with a threaded tapered hole 9 at its center which intersects the slot. The ferrule 10 of the shaft or handle 11 has its end tapered and threaded to engage the hole 9. Thus it 50 will be seen that after the plug has been put in position, the ferrule is passed through the hole 6 into the hole 9 in the plug, and by screwing the ferrule in said hole 9, the plug is expanded so that it will be firmly 55 held in the hole 5 and cannot turn therein.

Thus the head can be readily adjusted with respect to the shaft by loosening the ferrule to permit movement of the plug in the head and then turning the plug through means of the shaft to place the head in the desired 60 position relative to the shaft. Then the ferrule is tightened in the plug to expand the same in the head, which will hold the parts in adjusted position.

This invention provides a club, the head 65 of which can be adjusted to suit different players and enables the plug to be used either as a right hand one or a left hand one and it also enables either face to be used as a striking face.

In the modification shown in Figure 5, the 70 threaded hole 9' formed in the plug 7' extends entirely through the plug so that when the shaft is screwed into the plug, its end, striking the wall of the opening in the 75 head in which the plug is placed, will cause the plug to frictionally engage a part of the head and thus the parts will be locked in adjusted position. In this form of the invention, it is not necessary to split the plug 80 nor to taper the hole therein, though this may be done if desired.

It is thought from the foregoing description that the advantages and novel features 85 of my invention will be readily apparent.

I desire it to be understood that I may make changes in the construction and in the combination and arrangement of the several parts, provided that such changes fall within the scope of the appended claims.

90 What I claim is:

1. A golf club comprising a head, a plug rotatably mounted in the center of the head, said plug having a slot extending longitudinally therein and a threaded tapered 95 hole intersecting the slot, the head having an elongated hole in its top which exposes a portion of the plug and a shaft having its lower end threaded and tapered to engage the hole in the plug to permit expansion of 100 the plug by the shaft.

2. A golf club comprising a head having a hole transversely arranged therein and opening out through one side of the head, a plug in said hole having a threaded hole 105 therein, the head having an elongated hole in its top which exposes a portion of the plug and a shaft having a threaded end engaging the hole in the plug and means for causing the plug to frictionally engage the 110

head when the end of the shaft is placed in the hole in the plug to lock the parts in adjusted position.

3. A golf club comprising a head, a shaft, a plug rotatably mounted in the head and having a hole therein for receiving the end of the shaft, the head having an elongated

hole in its top which permits the shaft to be placed in the hole in the plug and means for causing the plug to frictionally engage the head when the end of the shaft is placed in the hole in the plug. 10

In testimony whereof I affix my signature.

RALPH N. LONGSWORTH.
